UNITED STATES PATENT OFFICE

EDWARD L. COMBS, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA

DESIGN FOR A RADIOCABINET

Application filed April 17, 1930. Serial No. 35,298. Term of patent 7 years.

To all whom it may concern:

Be it known that I, EDWARD L. COMBS, a citizen of the United States, residing in Philadelphia, Pennsylvania, have invented a new, original, and ornamental Design for Radiocabinet, of which the following is a specification, reference being had to the accompanying drawings, forming part thereof, in which:

Figure 1 is a front elevation of a radio cabinet made in accordance with my invention, and

Fig. 2 is a side elevation.

I claim:

The ornamental design for a radio cabinet, as shown.

EDWARD L. COMBS.
